UNITED STATES PATENT OFFICE

WOLFGANG HEYDEMANN, OF KIEL-DIETRICHSDORF, GERMANY, ASSIGNOR TO FRIED. KRUPP GERMANIAWERFT AKTIENGESELLSCHAFT, OF KIEL-GAARDEN, PRUSSIA, GERMANY

INTERNAL-COMBUSTION ENGINE

Application filed October 31, 1928, Serial No. 316,286, and in Germany November 21, 1927.

The invention relates to vertical two stroke cycle internal combustion engines, in particular multi-cylinder marine Diesel engines of high power, in which the cylinders of the 5 scavenging pumps are arranged immediately beside the working cylinders, in order to simplify the drive of the scavenging pumps. In known engines of this type the suction and pressure valves of the scavenging pumps 10 have vertical axes and are arranged round the scavenging pumps in concentric superimposed series. This arrangement suffers however from the drawback that the upper portion of the engine projects considerably 15 in lateral direction beyond the base plate, because the working cylinder, the scavenging pumps, and their valve heads are located side by side, see Figures 1 and 2 of the drawing. The resulting great width of the upper 20 portion of the engine is particularly troublesome with marine engines, as cabin gangways extend about at the level of the cylinders and the space required for the former is restricted by the cylinders.

25 The invention has for its object a two stroke cycle internal combustion engine of the above-mentioned type that is free from the drawback set forth above. According to the invention the axes of the suction and pressure valves for the scavenging pumps extend 30 horizontally and these valves are arranged on both sides of the scavenging pumps.

The subject-matter of the invention is illustrated by way of example in the accompanying drawing, in which

35 Figures 1 and 2 show in vertical longitudinal section and in top view, respectively, a two stroke cycle internal combustion engine fitted with a valve arrangement of known design, whilst

40 Figures 3 and 4 illustrate in a similar manner an engine of the same construction but having the scavenging pump valves arranged according to the invention.

45 Referring to these figures, A denotes a working cylinder of a multicylinder marine Diesel engine which cylinder rests on the columns B¹ B². The piston C reciprocating in the cylinder A transmits its motion by the 50 piston rod D to the cross head E and from

there by the rod F to the crank G of the engine shaft. Immediately beside each working cylinder is arranged the corresponding scavenging pump cylinder H the piston K of which is actuated through the intermediary 55 of the piston rod L by an arm P fixed on the cross head E of the engine. The scavenging pump is a double-acting one. The air is sucked in from the outside during the downward stroke by the suction valves M¹ and 60 during the upward stroke by the suction valves M². In the first case it passes into the compressed air chamber h¹ through the pressure valves N² and in the latter case 65 through the pressure valves N¹, from which chamber it passes through the scavenging ports a¹ immediately connected thereto, of the working cylinder. Figures 3 and 4 show the new arrangement of the valves on both 70 sides of the pump cylinders, the axes of the valves extending horizontally.

As may be seen by comparing the two arrangements illustrated in Figures 1, 2 and 3, 4, the arrangement according to the invention makes possible a considerably narrower 75 construction of the upper portion of the engine.

The lateral arrangement of the valves beside the pump cylinders affords the further advantage of more total space being at disposal for these valves, so that greater valve sections can be located in the upper portion of the engine without increasing its structural width, whereby the number of the valves to be provided may be reduced.

80 What I claim and desire to secure by Letters Patent is:—

A vertical two stroke cycle internal combustion engine having scavenging pumps with cylinders arranged immediately beside the corresponding working cylinders, the suction and pressure valves of said pumps being arranged on both sides of each corresponding pump cylinder, and between said pump cylinders, and having horizontal axes. 95

The foregoing specification signed at Hamburg, Germany, this eleventh day of October, 1928.

WOLFGANG HEYDEMANN.
